UNITED STATES PATENT OFFICE

OTTO HOFFMANN, OF WOODHAVEN, NEW YORK, ASSIGNOR TO ART FIXTURES, INC.,
OF NEW YORK, N. Y., A CORPORATION OF NEW YORK

DESIGN FOR A CHANDELIER OR SIMILAR ARTICLE

Application filed January 22, 1930. Serial No. 34,220. Term of patent 3½ years.

To all whom it may concern:

Be it known that I, OTTO HOFFMANN, a citizen of Germany, residing at Woodhaven, Long Island, in the county of Queens, in the State of New York, have invented a new, original, and ornamental Design for a Chandelier or Similar Article, of which the following is a specification, reference being had to the accompanying drawing, forming part thereof.

Fig. 1 is a plan view of a chandelier or similar article showing my new design.

Fig. 2 is a front view thereof.

I claim:

The ornamental design for a chandelier or similar article as shown.

OTTO HOFFMANN.
